UNITED STATES PATENT OFFICE

CHARLES M. MEAD, OF LOS ANGELES, CALIFORNIA

COLLAR CARD FOR FLAT FORM LAUNDERED ATTACHED COLLAR SHIRTS

Application filed September 15, 1930. Serial No. 481,851.

This invention relates to the art of holding the fronts of attached shirt collars flat and smooth in flat form laundered shirts having attached collars.

6 The bosom edges of such shirts are buttoned together and there has been placed between the collar points and the shirt bosom of flat form laundered shirts, a flat card having a recess cut upward from the lower 10 edge of the card, and adapted to allow the card to be slipped downward with the edges of the recess between the shirt front and the button which holds the neck band ends together after the shirt is laundered in flat 15 form; and when the card is thus secured to the shirt front, the collar points are brought into flat form position over the card.

It requires considerable time, skill, and 20 attention to apply such flat form collar holding cards in place with their upper edges seated in the collar folds and the edges of the recess inserted under the button.

An object of this invention is to provide 25 a flat form attached shirt collar card that can be secured in place with less requirement of skill, with less expenditure of care, attention and time, and with greater ease, than with the former flat form attached collar card or slip.

30 An object of this invention is to provide means for securing the flat slip in true position for holding in flat form the attached collars of shirts laundered to flat form.

In carrying out this invention I have provided a flat cardboard anchor templet having 35 a terminally widened shank, an obtuse crown at one end and an oval stock at the other end of the shank, and flat obtuse arm extensions of the crown, the edges of which extensions 40 are spaced from, and extend beyond, the stock, when in flat form; so that when the arms are placed in the fold of the collar of a flat form laundered shirt, the shank may be bent and the stock folded down inside the 45 neck band, and into practical parallelism with said crown and arms, thus to hold the collar ends in true position with the collar points and the shirt under such points flat and smooth.

50 The advantages of the invention are that

the device may be cut out of flat cardboard with great rapidity and at very slight expense; may be readily assembled and packaged in flat form for transportation; may be more easily handled by the fingers of the 55 operators, so that the work of applying and removing them from the shirt may be done more easily and quickly and with less likelihood of displacement, fumbling, crumpling or dropping, than with collar flat forms here- 60

65 Other objects, advantages and features of invention may appear from the accompanying drawing, the subjoined detailed description and the appended claims.

The invention will be understood by reference to the accompanying drawing, in which;

Figure 1 is a fragmental view of a flat laundered attached-collar shirt to which the anchor templet is shown applied; a portion 70 of the collar being broken away to expose the end of one of the anchor arms, and dotted lines being used to indicate the outer lapped end of the collar band and its securing button; dash lines being employed to indicate 75 the position of the stock folded inside the collar band, and dot and dash lines indicating the flat position of the stock.

Fig. 2 is a face view of the anchor in its 80 flat form as a manufacture.

Fig. 3 is an edge view looking up at the 85 edges of the anchor crown and the stock, as in the folded position of Fig. 1, omitting the shirt band and collar shown in such figure.

The attached collar 1, neck band 2, lapping ends 3 and bosom 4 of the shirt 5 are all 90 of common construction, and are shown in the flat form customary for finishing laundered shirts in flat form.

The cardboard anchor templet comprises a terminally broadened shank 6, a triangular rounded-nose plate 7 at one end of the shank and an oval stock 8 at the other end of the shank; the plate comprising oblique rounded arm extensions 9 embracing a triangular corner space 10 open at one side 11, and accommodating the shank and stock so that in flat form the plate is sufficiently stiff to be readily handled by the operator's fingers 100

without bending or distortion of plate, shank or stock, and can be shoved up under the collar and into the end folds thereof, while the shank is positioned between such fold ends, 5 and then the oval stock can be brought into position inside the shirt, thus bending the shank over the collar band and into practical parallelism with the nose and arms of the plate, thus to hold the collar ends flat and 10 in true position.

In practical manufacture, a row of dies, not shown, may be provided, extending across the platen of a printing press, and the cardboard may be fed to the press from a roll, not 15 shown, and the anchors may be assembled and boxed in a manner well known in the art of disposing of printing-press card products.

It is understood that the flat surfaces of the anchor may be supplied with advertisements, 20 announcements or other printed matter, not shown, and that the printing may be done on the cardboard either before or after the anchors are stamped out.

The rounding nose and arms shown are 25 sufficiently stiff to be easily caught by the fingers and shoved up under the collar points, and into the folds of the collar for the purpose, as there is no slot or recess to weaken it, and when so placed a stroke on the stock will 30 bend the shank at the middle, the widened terminals causing the bend to be there located so that the work may be quickly and smoothly effected.

By reason of the oval form of the stock and 35 anchor arms, the work is not subject to interference from contact of corners that might cause the arms or the stock to bend or twist out of true form during the operation of bringing the card to true position.

40 I claim:—

1. A device for holding in position the neck band ends and attached collar of a flat form laundered shirt, comprising a flat cardboard anchor having a terminally widened shank, 45 an obtuse crown at one end, and an oval stock at the other end of the shank and flat obtuse arm extensions of the crown, edges of which are spaced from and extend beyond the stock when in flat form; so that when the arms are 50 placed in the fold of the collar of a flat form laundered shirt, the shank may be bent and the stock folded down inside the neck band, and into practical parallelism with said crown and arms, thus to hold the collar ends 55 in true position.

2. A flat cardboard anchor templet comprising a terminally broadened shank; a triangular rounded-nose plate at one end of the shank and an oval stock at the other end of 60 the shank; said plate comprising oblique rounded arm extensions embracing a triangular corner space open at one side so that in flat form the plate is sufficiently stiff to be readily handled by an operator's fingers 65 without bending or distortion of the plate, the

shank or the stock; and can be shoved up under the collar and into the ends of the fold thereof while the shank is positioned between such fold ends; and such shank can then be bent over the collar band and the stock 70 brought into the shirt behind the front of such band.

In testimony whereof, I have hereunto set my hand at Los Angeles, California, this 5th day of Sept. 1930.

CHARLES M. MEAD.
